RAILWAY SIGNALING SYSTEM

Henry S. Young, Wilkinsburg, Pa., assignor to
The Union Switch & Signal Company, Swiss-
vale, Pa., a corporation of Pennsylvania

Original application August 30, 1934, Serial No.
742,095. Divided and this application Decem-
ber 14, 1938, Serial No. 245,717

16 Claims. (Cl. 246—53)

My invention relates to railway signaling systems of the type involving light signals which are approach lighted.

One object of my invention is to provide means for 5 checking the continuity of the lamp filament of a signal of the type described while the lamp is extinguished.

Another object of my invention is to provide a restrictive indication for trains approaching an 10 approach lighted signal having a burned out lamp.

Other objects of my invention will appear as the description proceeds.

The present application is a division of my pending application Serial No. 742,095, filed August 15 30, 1934, now Patent No. 2,143,967, granted January 17, 1939, for Railway signaling systems.

I shall describe one form of signaling system embodying my invention, and shall then point out the novel features thereof in claims.

20 In the accompanying drawings, Figs. 1 and 1^a are diagrammatic views which, when placed end to end with Fig. 1^a on the right, show my invention applied to a signaling system employing an upper and a lower signal unit for each signal.

25 Similar reference characters refer to similar parts in each of the two views.

Referring to the drawings, the reference characters 1 and 1^a designate the track rails of a stretch of railway track along which traffic normally moves in the 30 direction indicated by the arrow. These track rails are divided by means of insulated joints 2 into a plurality of blocks, three of these blocks A—B, B—C and C—D being shown complete in the drawings. Each of these blocks comprises a single track 35 section, and each track section is provided with a track circuit including a battery 50 and a track relay TR. Located at the entrance end of each section is a signal S which, as here shown, comprises two signal mechanism units, each designated by the same reference character as the reference character for the 40 associated signal with a distinguishing subscript.

Each of these units, as here shown, is of the type 45 commonly known as a searchlight signal, and comprises an armature 5 mounted to rotate between an intermediate position to which it is biased, and two extreme positions. Each armature 5 is controlled by an armature winding 6, and is polarized by the field from a permanent magnet or an electromagnet (not shown) in such a manner that when the winding 6 is energized, the armature 5 will rotate to its right-hand or left-hand extreme position according as winding 6 is then supplied with current of normal or reverse polarity, respectively. Attached to each armature 5 to rotate therewith are three colored 50 roundels G, R, and Y, which are arranged to be dis-

posed in the path of a beam of light projected from an associated lamp L according as the armature 5 occupies its right-hand extreme position, its intermediate position or its left-hand extreme position, respectively. For convenience in illustration, each lamp L in the drawing is shown disposed above the associated roundels, but it will be readily understood that in actual practice each lamp will be located directly back of the associated roundel and will have associated therewith a suitable optical system, not shown, for projecting a beam of light from the lamp. The signals S each indicate "proceed," "stop" or "caution" according as the roundel G, R, or Y is in front of the associated lamp L when this lamp is lighted. Operatively connected with each armature 5 is a circuit controller comprising two movable contact fingers 7 and 8. The movable contact finger 7 cooperates with a fixed contact 7^a to close a contact 7—7^a when the armature occupies its right-hand extreme position, and with a fixed contact 7^b to close a contact 7—7^b when the armature occupies its intermediate position or its left-hand extreme position; while the movable contact finger 8 cooperates with a fixed contact 8^a to close a contact 8—8^a when the armature occupies its left-hand extreme position, and with a fixed contact 8^b to close a contact 8—8^b when the armature occupies its intermediate or its right-hand extreme position. A signal of the type described is disclosed and claimed in Letters Patent of the United States No. 1,864,224, granted to Wesley B. Wells, on June 21, 1932, for Light signals.

In actual practice, both signal mechanism units will usually be secured to the same pole or mast with the one mechanism disposed above the other. With this arrangement, when both mechanisms are displaying a red aspect, the signal indicates "stop"; when the upper mechanism displays a yellow aspect and the lower mechanism displays a red aspect, the signal indicates "caution"; when the upper mechanism displays a yellow aspect and the lower mechanism a green aspect, the signal indicates approach restricting; and when the upper mechanism displays a green aspect and the lower mechanism a red aspect, the signal indicates "proceed."

Associated with each signal are a polarized distant relay DR, an approach lighting relay ALR, an auxiliary relay AR, a reactor J, a signal repeater relay SR, a light-out relay LOR, a power-off relay POR, a transformer T, and a battery E. Each reactor J has the same reactance as the associated light-out relay LOR.

The winding 6 of each signal mechanism S₁ is controlled by the associated track relay TR and by the associated distant relay DR. Referring particularly to the winding 6 of signal mechanism S₁,

when track relay TR^A is energized and distant relay DR^A is energized in its normal direction so that its polar contacts are swung toward the left, as shown in the drawing, this winding is supplied with current 5 of normal polarity over a circuit which passes from battery E^A , through wires 180, 181, 182, 183, 184 and 185, front contact 186 of track relay TR^A , wires 187 and 188, polar contact 189—189^a of relay DR^A , wire 190, front contact 191—191^a of relay DR^A , wire 192, 10 winding 6 of signal mechanism S_1^A , wire 194, front contact 195—195^a of relay DR^A , wire 196, polar contact 197—197^a of relay DR^A , and wires 198, 199 and 200 back to battery E^A . When, however, track relay TR^A is energized and distant relay DR^A is 15 energized in its reverse direction so that its polar contacts are swung toward the right, winding 6 of signal mechanism S_1^A is then supplied with current of reverse polarity over a circuit which passes from battery E^A , through wires 180, 181, 182, 183, 184 and 185, front contact 186 of track relay TR^A , wires 187, 188 and 201, polar contact 197—197^b of relay DR^A , wire 196, front contact 195—195^a of relay DR^A , wire 194, winding 6 of signal mechanism S_1^A , wire 192, front contact 191—191^a of distant relay 20 25 DR^A , wire 190, polar contact 189—189^b of distant relay DR^A , and wires 198, 199 and 200 back to battery E^A . When track relay TR^A is energized and distant relay DR^A is deenergized, winding 6 of signal mechanism S_1^A is then supplied with current of 30 reverse polarity over a circuit which passes from battery E^A , through wires 180, 181, 182, 183, 184 and 185, front contact 186 of track relay TR^A , wire 187, back contact 195—195^b of distant relay DR^A , wire 194, winding 6 of signal mechanism S_1^A , wire 192, 35 back contact 191—191^b of distant relay DR^A , and wires 202, 198, 199 and 200 back to battery E^A . When winding 6 of signal mechanism S_1^A is supplied with current of normal polarity, this signal mechanism will, of course, occupy the position in which the 40 green roundel is disposed in front of the associated lamp L , and when winding 6 of this signal mechanism is supplied with current of reverse polarity, this signal mechanism will occupy the position in which the yellow roundel is disposed in front of the 45 associated lamp L .

The winding 6 of each signal mechanism S_2 is controlled by the associated distant relay DR , by the associated signal mechanism S_1 , by the associated track relay TR , and by the associated auxiliary relay AR . Referring particularly to winding 6 of 50 signal mechanism S_2^A , the circuit for this winding passes from battery E^A , through wires 180 and 203, front contact 204 of auxiliary relay AR^A , wire 205, front contact 206 of track relay TR^A , wire 207, 55 contact 8—8^a of signal mechanism S_1^A , wire 17, contact 7—7^b of signal mechanism S_1^A , wire 208, polar contact 209—209^b of distant relay DR^A , wire 210, front contact 211 of distant relay DR^A , wire 212, winding 6 of signal mechanism S_2^A , wire 213, front 60 contact 214 of distant relay DR^A , wire 215, polar contact 216—216^b of distant relay DR^A , and wires 217, 199 and 200 back to battery E^A . This circuit is closed only when track section A—B is unoccupied and signal mechanism S_1^A is swung to its left-hand 65 extreme position, and the current supplied to winding 6 of signal mechanism S_2^A over this circuit is of such polarity that when this circuit is closed, the signal mechanism will be swung to the position in which the green roundel is disposed in front of the associated lamp.

70 Each signal repeater relay SR is controlled by the associated signal mechanisms S_1 and S_2 , by the associated track relay TR and by the associated auxiliary relay AR . Referring particularly to relay SR^A , one 75 circuit for this relay is closed when auxiliary relay

AR^A and track relay TR^A are both energized, and the signal mechanisms S_1^A and S_2^A of signal S^A occupy their proceed positions, and passes from battery E^A , through wires 180 and 203, front contact 204 of auxiliary relay AR^A , wire 205, front contact 206 of track relay TR^A , wire 207, contact 7—7^a of signal mechanism S_1^A , wire 17, contact 8—8^b of signal mechanism S_1^A , wires 220 and 221, winding of relay SR^A , and wires 199 and 200 back to battery E^A . Another circuit for relay SR^A is closed when track relay TR^A and auxiliary relay AR^A are both energized and signal mechanisms S_1^A and S_2^A occupy the positions in which the yellow and green roundels of these signal mechanisms are disposed respectively in front of the associated lamps L_1^A and L_2^A , this latter circuit passing from battery E^A through wires 180 and 203, front contact 204 of auxiliary relay AR^A , wire 205, front contact 206 of track relay TR^A , wire 207, contact 8—8^a of signal mechanism S_1^A , wire 17, contact 7—7^b of signal mechanism S_1^A , wire 208, contact 7—7^a of signal mechanism S_2^A , wire 221, winding of relay SR^A , and wires 199 and 200 back to battery E^A .

At each signal location, there is provided a transformer designated by the reference character T with a suitable distinguishing exponent, and a "power-off" relay designated by the reference character POR with a suitable distinguishing exponent. The primary winding 40 of each transformer T is constantly connected with the terminals Z and O of a suitable source of alternating current not shown in the drawing, while the secondary winding 41 of each transformer T is constantly connected with the winding of the associated power-off relay. It will be seen, therefore, that each power-off relay will be 35 energized at all times except in the event that the alternating current supply fails.

Each distant relay DR is controlled by the associated track relay TR , by the signal repeater relay SR associated with the two signal mechanisms S_1 and S_2 of the signal S next in advance, by the track relay TR associated with the signal next in advance, and by the auxiliary relay AR associated with the signal next in advance. Referring particularly to relay DR^A , for example, one circuit for this relay passes from battery E^B , through wires 180 and 203, front contact 204 of auxiliary relay AR^B , wire 205, front contact 206 of track relay TR^B , wire 207, contact 8—8^a of signal mechanism S_1^B , wire 222, winding of approach lighting relay ALR^B , wire 233, front contact 224—224^a of signal repeater relay SR^B , line wire 225, front contact 226 of track relay TR^A , wire 227, winding of distant relay DR^A , line wire 251, front contact 228—228^a of relay SR^B , and wires 229 and 200 back to battery E^B . Another circuit for relay DR^A is similar to the circuit just traced with the exception that this latter circuit includes back contacts 224—224^b and 228—228^b of signal repeater relay SR^B instead of front contacts 224—224^a and 228—228^a this relay. A third circuit for distant relay DR^A is similar to the circuit first traced for this relay with the exception that this latter circuit includes contact 7—7^a of signal mechanism S_1^B and wire 17 in place of contact 8—8^a.

It will be noted that each of the circuits for each distant relay includes the approach lighting relay associated with the signal next in advance, and it follows that each approach lighting relay will be energized except when the block next in the rear of the associated signal, or the block next in advance of the associated signal is occupied.

Each lamp L_1 is provided with two energizing circuits one of which is closed when the associated approach lighting relay ALR is deenergized and the associated power-off relay POR is energized, and

the other of which is closed when the associated approach lighting relay ALR and power-off relay POR are both deenergized. Referring particularly to lamp L_1^A , the circuit for this lamp which is closed when approach lighting relay ALR^A is deenergized and power-off relay POR^A is energized may be traced from the right-hand terminal of secondary 41 of transformer T^A through wires 235, 182, 183, 184, 236, the filament of lamp L_1^A , wire 237, the winding of relay LOR^A, wire 238, back contact 239-239^b of approach lighting relay ALR^A, wire 240, front contact 241-241^a of power-off relay POR^A, and wire 242 to the left-hand terminal of secondary 41 of transformer T^A. The circuit for lamp L_1^A which is closed when approach lighting relay ALR^A and power-off relay POR^A are both deenergized may be traced from battery E^A through wires 180, 181, 182, 183, 184, and 236, lamp L_1^A , wire 237, the winding of light-out relay LOR^A, wire 238, back contact 239-239^b of approach lighting relay ALR^A, wire 240, back contact 241-241^a of power-off relay POR^A, and wires 229 and 200 to battery E^A.

Each lamp L_2 is likewise provided with two circuits one of which is closed when the associated approach lighting relay ALR is deenergized and the associated power-off relay POR is energized and the other of which is closed when the associated approach lighting relay ALR^A is deenergized and the associated power-off relay POR^A is also deenergized. Referring particularly to lamp L_2^A , for example, the one circuit for this lamp passes from the right-hand terminal of secondary 41 of transformer T^A through wires 235, 182, 183 and 243, the filament of lamp L_2^A , reactor J^A, back contact 250 of approach lighting relay ALR^A, wire 240, front contact 241-241^a of power-off relay POR^A, and wire 242 to the left-hand terminal of secondary 41 of transformer T^A. The other circuit for lamp L_2^A may be traced from battery E^A, through wires 180, 181, 182, 183 and 243, the filament of lamp L_2^A , reactor J^A, back contact 250 of approach lighting relay ALR^A, wire 240, back contact 241-241^b of power-off relay POR^A and wires 229 and 200 to battery E^A.

It will be noted that each of the circuits for the lamps L_1 includes the winding of the associated light-out relay and that the one circuit is energized by alternating current whereas the other circuit is energized by direct current. Each light-out relay is so constructed that it will operate on either alternating or direct current, and the parts are so proportioned that when either one of the circuits for the associated lamp is closed, the relay will become energized.

It will also be noted that each of the circuits for the lamp L_2^A includes a reactor J^A which as was previously pointed out has the same reactance as the winding of the associated light-out relay LOR^A. It will further be noted that the circuits for the lamps L_2 are supplied with energy from the same sources as the corresponding circuits for the lamps L_1 , and it follows that both lamps will be supplied with current of the same magnitude.

Each auxiliary relay AR is provided with two circuits, one of which is closed when the associated approach lighting relay ALR is energized and the associated light-out relay LOR is deenergized, and the other of which is closed when the associated light-out relay is energized. Referring particularly to relay AR^A, the one circuit for this relay includes the filament of lamp L_1^A and passes from battery E^A through wires 180, 181, 182, 183, 184 and 236, the filament of lamp L_1^A , wire 237, the winding of light-out relay LOR^A, wire 238, front contact 239-239^a of approach lighting relay ALR^A, wire 244, back

contact 245-245^b of light-out relay LOR^A, wire 246, the winding of relay AR^A, and wire 247 back to battery E^A. The other circuit for relay AR^A passes from battery E^A, through wires 180, 181 and 182, front contact 245-245^a of light-out relay LOR^A, wire 246, the winding of auxiliary relay AR^A, and wire 247 back to battery E^A.

It will be noted that one circuit for relay AR includes the winding of the associated light-out relay LOR, and the filament of the associated lamp L_1 . The resistance of each auxiliary relay AR is sufficiently high so that when this circuit is closed, the associated light-out relay LOR will not open its back contacts, and the lamp L_1 will not become lighted.

As shown in the drawing, blocks A-B, B-C and C-D are all unoccupied, but the block to the right of point D is occupied by a train W. Track relays TR^A, TR^B and TR^C are therefore all energized, but track relay TR^D is deenergized. With track relay TR^D deenergized all circuits for the winding 6 of signal mechanism S^D are interrupted at front contact 186 of this track relay, and the sole circuit for winding 6 of signal mechanism S^D is open at front contact 206 of this track relay with the result that the red roundels of both signal mechanisms S^D and S^D₂ are disposed in front of the associated lamps L_1^D and L_2^D . Furthermore, with track relay TR^D deenergized, all circuits for relays DR^D, DR^D, SR^D and ALR^D are open so that these relays are all deenergized. The power-off relays POR are all energized, and since power-off relay POR^D is energized and approach lighting relay ALR^D is deenergized, the circuits for lamps L_1^D and L_2^D including the secondary 41 of transformer D are both closed. The lamps L_1^D and L_2^D are therefore both lighted so that signal S^D indicates "stop." Light-out relay LOR^D is energized by virtue of the circuit which is closed for lamp L_1^D , and auxiliary relay AR^D is therefore energized over the circuit including front contact 245-245^b of relay LOR^D.

Track relay TR^C being energized and distant relay DR^C being deenergized, winding 6 of signal mechanism S^C is supplied with current of reverse polarity and winding 6 of signal mechanism S^C₂ is deenergized. The yellow roundel of signal mechanism S^C is therefore disposed in front of the associated lamp L_1^C , and the red roundel of signal mechanism S^C₂ is disposed in front of the lamp L_2^C . With the signal mechanisms S^C and S^C₂ in the positions just described, all circuits for relay SR^C are open, and this relay is therefore deenergized. Since track relays TR^B and TR^C are both energized and relay SR^C is deenergized, distant relay DR^B is energized in the reverse direction and approach lighting relay ALR^C is therefore picked up. Lamps L_1^C and L_2^C are accordingly both extinguished and light-out relay LOR^C is deenergized. Auxiliary relay AR^C is energized over the circuit including the filament of lamp L_1^C , front contact 239-239^a of relay AR^C and back contact 245-245^b of relay LOR^C.

With distant relay DR^B energized in the reverse direction and track relay TR^B energized, winding 6 of signal mechanism S^B is supplied with current of reverse polarity and winding 6 of signal mechanism S^B₂ is supplied with current of normal polarity. Signal mechanism S^B₁, therefore, occupies its extreme left-hand position in which the yellow roundel Y of this mechanism is disposed in front of the lamp L_1^B and signal mechanism S^B₂ occupies its extreme right-hand position in which the green roundel G of this latter mechanism is disposed in front of the lamp L_2^B . Signal mechanism S^B₁ and S^B₂ being in the positions just described, signal repeater relay SR^B is energized and since track relay TR^A is also ener-

gized, distant relay DR^A is energized in the normal direction and approach lighting relay ALR^B is picked up. Approach lighting relay ALR^B being picked up, the lamps L_1^B and L_2^B are both deenergized, 5 and light-out relay LOR^B is also deenergized. With approach lighting relay ALR^B picked up and light-out relay LOR^B deenergized, the circuit for auxiliary relay AR^B including the filament of lamp L_1^B is closed, and this latter relay is therefore also 10 energized.

Distant relay DR^A being energized in its normal direction, winding 6 of signal mechanism S_1^A is supplied with current of normal polarity, so that the green roundel of this signal mechanism is in 15 front of the lamp L_1^A , and winding 6 of signal mechanism S_2^A is deenergized, so that the red roundel of this mechanism is in front of the lamp L_2^A . Approach lighting relay ALR^A is energized, and all circuits for lamps L_1^A and L_2^A are therefore 20 open at the contacts 239—239^b and 250 of relay ALR^A . Lamps L_1^A and L_2^A are therefore extinguished, and light-out relay LOR^A is deenergized. The circuit for auxiliary relay AR^A including back contact 245—245^b of light-out relay LOR^A and 239—239^a of 25 approach lighting relay ALR^A is closed, and this relay is therefore energized. Relay SR^A is energized over the circuit including front contact 204 of relay AR^A and contacts 7—7^a and 8—8^b of signal mechanism S_1^A .

30 With the apparatus in the position described, when the train W passes out of the section to the right of point D , track relay TR^D will pick up, thereby closing its front contacts 186, 206 and 226. When front contact 186 of track relay TR^D becomes 35 closed, a circuit for winding 6 of signal mechanism S_1^P including this contact and back contacts 191—191^b and 195—195^b of distant relay DR^B will become closed and signal mechanism S_1^P will therefore move to its left-hand extreme position in which 40 the yellow roundel Y is disposed in front of the lamp L_1^P . As soon as the signal mechanism S_1^P reaches this position, contact 8—8^a of this mechanism will become closed, and will complete one of the circuits for distant relay DR^C , thus causing this 45 relay to become energized in its reverse direction and approach lighting relay ALR^P to pick up. When approach lighting relay ALR^P picks up, the circuits which were previously closed for lamps L_1^P and L_2^P will become interrupted, and these lamps 50 will then become extinguished and light-out relay LOR^P will become deenergized. The deenergization of light-out relay LOR^P will interrupt the circuit which was previously closed for auxiliary relay AR^P at front contact 245—245^a of relay LOR^P , and 55 will complete the circuit for relay AR^P including back contact 245—245^b of relay LOR^P . Relay AR^P will not open its front contact 204 under these conditions, however, because of its slow releasing characteristic.

60 When distant relay DR^C becomes energized in its reverse direction, in the manner just described, the circuit which was previously closed for winding 6 of signal mechanism S_1^C including back contact 195—195^b and 191—191^b of relay DR^C becomes interrupted, and another circuit for winding 6 of signal mechanism S_1^P including front contacts 195—195^a and 191—191^a becomes closed. Signal mechanism S_1^P will remain in the position shown, however, because the current supplied to the winding 6 of this mechanism over both of these circuits flows through 65 the winding in the same direction. The energization of distant relay DR^C , under the conditions just described, also completes the circuit for winding 6 of signal mechanism S_2^C , and when this circuit becomes closed, 70 the mechanism moves to its extreme right-hand position in which the green roundel G is disposed in front of the lamp L_2^C . The movement of the signal mechanism S_2^C to the position just described completes the circuit for signal repeater relay SR^C including front contact 7—7^a of signal mechanism S_1^C , and relay SR^C therefore picks up, and reverses the polarity of the current supplied to distant relay DR^B , thus causing this relay to become energized in its normal direction. When relay DR^B becomes energized in 10 its normal direction, it interrupts the circuit which was previously closed for winding 6 of signal mechanism S_2^B , and this signal mechanism therefore moves to its intermediate position in which the red roundel R is disposed in front of the lamp L_2^B . When distant relay DR^B becomes energized in its normal direction it also interrupts the circuit which was previously closed for winding 6 of signal mechanism S_1^B at polar contacts 189—189^b and 197—197^b of this relay, and completes another circuit for winding 6 of signal mechanism S_1^B including polar contacts 189—189^a and 197—197^a of relay DR^B . When this latter circuit for winding 6 of signal mechanism S_1^B is closed, winding 6 is then supplied with current of normal polarity, and the mechanism of signal S_1^B therefore moves to the position in which the green roundel G is disposed in front of the lamp L_1^B . The movement of the two signal mechanisms S_1^B and S_2^B from the position in which they are shown in the drawing to the position just described, interrupts one circuit for relay SR^B and completes the other circuit for this 20 relay, but due to the slow releasing characteristic of relay SR^B , this relay does not open its front contacts under this condition.

I shall now assume that the parts are in the 25 position shown in the drawing and that the filament of lamp L_1^C becomes interrupted for some reason. Under this condition, the circuit which was previously closed for auxiliary relay AR^C will become interrupted at the lamp filament, and this relay will therefore become deenergized and open its front contact 204. The opening of this contact will interrupt the circuit which was previously closed for distant relay DR^B , thus causing this relay and approach lighting relay ALR^C to become deenergized. The deenergization of approach lighting relay ALR^C will complete one of the energizing circuits for lamp L_2^C , thus causing this lamp to become lighted. The deenergization of relay DR^B will interrupt the circuit which was previously closed for winding 6 of signal mechanism S_1^B including contacts 195—195^a and 191—191^a of relay DR^B , and will complete the circuit for winding 6 of signal mechanism S_1^P including contacts 195—195^b and 191—191^b of relay DR^B . This signal mechanism, however, will remain in the position shown since the current supplied to the winding 6 over both of these circuits flows through the winding in the same direction. The deenergization of relay DR^B will also interrupt the circuit which was previously closed for winding 6 of signal mechanism S_2^B at front contacts 211 and 214 of this relay, and this winding will therefore now become deenergized, thus causing signal mechanism S_2^B to move to the position in which the red roundel R is disposed in front of the lamp L_2^B . When signal mechanism S_2^B moves to this latter position, the opening of contact 7—7^a of this signal mechanism will deenergize signal repeater relay SR^B and this relay will therefore reverse the polarity of the current supplied to distant relay DR^A , thus causing signal mechanism S_1^P to move from the position shown to the position in which the yellow roundel Y is disposed at the front of the lamp L_1^P ; and the signal mechanism S_1^P to move from the position shown to the position in which the green roundel G is disposed in front of the associated 30 35 40 45 50 55 60 65 70 75 80 85 - lamp L_2^A . It will be seen, therefore, that when the lamp L_1 of a signal burns out when the block next in advance is occupied by a train, the signal mechanisms of the signal for the block next in rear will automatically be moved to such positions that if the associated lamps were then lighted due to the presence of a train in the second block in the rear, the signal for the block next in rear would then display a caution indication. It will also be seen that if the lamp L_1 of a signal burns out when the block next in advance of the associated block is occupied by a train, the signal mechanisms of the signal for the second block in rear of the section in question will automatically be moved to such positions that if the associated lamps were then lighted due to a train approaching the signal, the signal would display an approach restricting indication. It follows that under either of the conditions just described, an engineman approaching a signal in which the lamp L_1 is burned out will receive the same indications when he passes the two signals next in the rear of the signal having the burned out lamp as he would receive if the block immediately in advance of the signal having the burned out lamp were occupied, thus giving him ample opportunity to stop when he finally approaches the signal with the burned out lamp.

I shall next assume that with the parts in the position in which they are shown in the drawing, the lamp L_2^B burns out. Under this condition, auxiliary relay AR^B will become deenergized and will interrupt the circuit which was previously closed at the contact of this relay for winding 6 of signal mechanism S_2^B , thus causing this signal mechanism to move from the position in which the green roundel G is disposed in front of the lamp L_2^B to the position in which the red roundel R is disposed in front of this lamp. When signal mechanism S_2^B moves to this latter position, the circuit which was previously closed for relay SR^B will become interrupted so that this relay will become deenergized but the deenergization of this relay will have no effect on the apparatus because all circuits for relay DR^A will then be open at front contact 204 of relay AR^B and relay DR^A will already be deenergized. The deenergization of relay DR^A will cause signal mechanism S_1^A to move from the position shown to the position in which the yellow roundel Y is disposed in front of the lamp L_1^A . As a result, if a train now enters the block to the left of block A-B and causes approach lighting relay ALR^A to become deenergized, signal S_1^A will indicate caution instead of proceed. It follows that if signal lamp L_1 burns out when the two blocks next in advance of the associated signal are both unoccupied, the signal mechanisms of the signal next in the rear of the associated signal will be automatically moved to the same positions as when a lamp burns out, and the block next in advance of the associated signal is occupied.

Although I have herein shown and described only one form of signal system embodying my invention, it is understood that various changes and modifications may be made therein within the scope of the appended claims without departing from the spirit and scope of my invention.

Having thus described my invention, what I claim is:

1. In combination, a stretch of railway track divided into blocks, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; means for normally supplying the upper mechanism of each signal with current of normal polarity when the next three blocks in advance are unoccupied and with current of reverse polarity when either one or two blocks next in advance are unoccupied, means for supplying the lower winding of each signal with current of normal polarity when and only when the two blocks next in advance are unoccupied, means for lighting the lamps associated with a signal when a train occupies the block next in the rear or next in advance of the signal, and means effective if the filament of the lamp associated with the upper mechanism of a signal is broken and no train is approaching the signal or occupies the block next in advance thereof for conditioning the two signals next in the rear to display more restrictive indications.

2. In combination, a stretch of railway track divided into blocks, a track circuit for each block including a track relay, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; means for normally supplying the upper mechanism of each signal with current of normal polarity when the next three blocks in advance are unoccupied and with current of reverse polarity when either one or two blocks next in advance are unoccupied, means for supplying the lower winding of each signal with current of normal polarity when and only when the two blocks next in advance are unoccupied, means for lighting the lamps associated with a signal when a train occupies the block next in the rear or next in advance of the signal, and means effective if the filament of the lamp associated with the upper mechanism of a signal is broken and no train is approaching the signal or occupies the block next in advance thereof for conditioning the two signals next in the rear to display more restrictive indications.

3. In combination, a stretch of railway track divided into blocks, a track circuit for each block including a track relay, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; means for normally supplying the upper mechanism of each signal with current of normal polarity when the next three blocks in advance are unoccupied and with current of reverse polarity when either one or two blocks next in advance are unoccupied, means for supplying the lower winding of each signal with current of normal polarity when and only when the two blocks next in advance are unoccupied, means for lighting the lamps associated with a signal when a train occupies the block next in the rear or next in advance of the signal, and means effective if the filament of the lamp associated with the upper mechanism of a signal is broken and no train is approaching the signal or occupies the block next in advance thereof for conditioning the two signals next in the rear to display more restrictive indications.

4. In combination, a stretch of railway track divided into blocks, a track circuit for each block including a track relay, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; means for normally supplying the upper mechanism of each signal with current of normal polarity when the next three blocks in advance are unoccupied and with current of reverse polarity when either one or two blocks next in advance are unoccupied, means for supplying the lower winding of each signal with current of normal polarity when and only when the two blocks next in advance are unoccupied, means for lighting the lamps associated with a signal when a train occupies the block next in the rear or next in advance of the signal, and means effective if the filament of the lamp associated with the upper mechanism of a signal is broken and no train is approaching the signal or occupies the block next in advance thereof for conditioning the two signals next in the rear to display more restrictive indications.

5. In combination, a stretch of railway track divided into blocks, a track circuit for each block including a track relay, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; means for normally supplying the upper mechanism of each signal with current of normal polarity when the next three blocks in advance are unoccupied and with current of reverse polarity when either one or two blocks next in advance are unoccupied, means for supplying the lower winding of each signal with current of normal polarity when and only when the two blocks next in advance are unoccupied, means for lighting the lamps associated with a signal when a train occupies the block next in the rear or next in advance of the signal, and means effective if the filament of the lamp associated with the upper mechanism of a signal is broken and no train is approaching the signal or occupies the block next in advance thereof for conditioning the two signals next in the rear to display more restrictive indications.

6. In combination, a stretch of railway track divided into blocks, a track circuit for each block including a track relay, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; means for normally supplying the upper mechanism of each signal with current of normal polarity when the next three blocks in advance are unoccupied and with current of reverse polarity when either one or two blocks next in advance are unoccupied, means for supplying the lower winding of each signal with current of normal polarity when and only when the two blocks next in advance are unoccupied, means for lighting the lamps associated with a signal when a train occupies the block next in the rear or next in advance of the signal, and means effective if the filament of the lamp associated with the upper mechanism of a signal is broken and no train is approaching the signal or occupies the block next in advance thereof for conditioning the two signals next in the rear to display more restrictive indications.

of the signal next in advance, a front contact of the track relay associated with the signal next in advance, and a front contact of the auxiliary relay associated with the signal next in advance; a circuit 5 for each signal repeater relay controlled by both signal mechanisms of the associated signal, by the associated track relay, and by the associated auxiliary relay and closed only when the lower mechanism of the associated signal is energized by 10 current of normal polarity, the upper mechanism of the associated signal is energized by current of reverse polarity, the associated track relay is energized and the associated auxiliary relay is energized; another circuit for each signal repeater relay controlled by the upper signal mechanism of each signal and by the associated track and auxiliary relays, and closed when the upper mechanism of the associated signal is supplied with current of normal 15 polarity and the associated track and auxiliary 20 relays are both energized, means for energizing each auxiliary relay in series with the lamp of the upper signal mechanism of the associated signal and the winding of the associated light-out relay when the associated approach lighting relay is energized 25 and the associated light-out relay is deenergized, means for energizing each auxiliary relay when the associated approach lighting relay is energized, means for energizing the lamp of the upper mechanism of each signal in series with the associated 30 light-out relay when the associated approach lighting relay is deenergized, and means for energizing the lamp of the lower mechanism of each signal when the associated approach lighting relay is deenergized.

3. In combination with a section of railway track, 35 a light signal for governing the entrance of traffic into said section, said signal having a lamp, a polarized line relay for governing the indication provided by said signal in accordance with the polarity of the current supplied thereto, a polarized line circuit for 40 said line relay supplied with current of one or another polarity in accordance with traffic conditions in advance, a checking relay for said signal, an energizing circuit for said checking relay including the lamp filament of said signal but incapable of 45 lighting said lamp, and means controlled by said checking relay effective upon the interruption of the flow of said checking current due to failure of said filament for controlling the traffic approaching said section.

50 4. In combination with a section of railway track, a light signal for governing the entrance of traffic into said section, said signal having a lamp, a polarized line relay for governing the indication provided by said signal in accordance with the polarity of the current supplied thereto, a polarized line circuit for 55 said line relay supplied with current of one or another polarity in accordance with traffic conditions in advance, a checking relay for said signal, an energizing circuit for said checking relay including the lamp filament of said signal but incapable of 60 lighting said lamp, and means controlled by said checking relay effective upon the interruption of the flow of said checking current due to failure of said filament for causing said signal to display a restrictive indication irrespective of traffic conditions in 65 advance thereof.

5. In combination, a stretch of railway track divided into blocks, a light signal for each block for governing traffic entering therein, each of said signals having a lamp, a polarized line relay for each signal for governing the indication provided by the signal in accordance with the polarity of the current supplied thereto, a polarized line circuit for each line relay supplied with current of one or another polarity 70 in accordance with traffic conditions in advance, a

75 checking relay for each signal, an energizing circuit for each checking relay including the lamp filament of the associated signal but incapable of lighting said lamp, and means governed by each checking relay and effective upon failure of the lamp filament of the associated signal for controlling the line circuit for the line relay associated with the signal next in the rear.

6. In combination, a stretch of railway track divided into blocks, a light signal for each block for governing traffic entering therein, each of said signals having a lamp, a polarized line relay for each signal for governing the indication provided by the signal in accordance with the polarity of the current supplied thereto, a polarized line circuit for each line relay supplied with current of one or another polarity in accordance with traffic conditions in advance, a checking relay for each signal, an energizing circuit for each checking relay including the lamp filament of the associated signal but incapable of lighting said lamp, a normally energized approach lighting relay for each signal, means governed by each checking relay and effective upon failure of the lamp filament of the associated signal for controlling the line circuit for the line relay associated with the signal next in the rear and for deenergizing said approach lighting relay, and means effective when said approach lighting relay is deenergized for causing the associated signal to display a restrictive indication irrespective of traffic conditions in advance thereof. 30

7. In combination with a section of railway track, an approach energized light signal for governing traffic entering said section, said signal having a lamp, a polarized line relay for said signal for governing the indication provided by the signal, a polarized line circuit for said relay controlled by traffic conditions in advance of said signal, means for at times supplying lighting current to said signal, means for at other times supplying a checking current of insufficient value to light said signal, and means effective upon an interruption in said checking current in the event of failure of the lamp of said signal for controlling the traffic approaching said section. 35

8. In combination, a stretch of railway track divided into blocks, an approach energized light signal for each block for governing traffic entering therein, each of said signals having a lamp, a polarized relay for each signal for governing the indication provided thereby, a lighting circuit for each signal, a normally energized checking circuit for 45 each signal including the lamp filament but ineffective to cause lighting thereof, a checking relay for each signal governed by the associated checking circuit, and a line circuit for each polarized line relay controlled by the checking relay for the signal next 50 in advance.

9. In combination, a stretch of railway track divided into blocks, an approach energized light signal for each block for governing traffic entering therein, each of said signals having a lamp, a polarized relay for each signal for governing the indication provided thereby, a normally energized approach lighting relay for each signal governed by traffic approaching the signal and effective when deenergized to cause the signal to become lighted, 65 a normally energized checking relay for each signal, a circuit for each checking relay including a front contact of the associated approach lighting relay and the lamp filament of the associated signal, and a line circuit for each polarized line relay including 70 a front contact of the checking relay next in advance.

10. In combination, a stretch of railway track divided into blocks, an approach energized light signal for each block for governing traffic entering therein, each of said signals having a lamp, a polar- 75

ized relay for each signal for governing the indication provided thereby, a normally energized approach lighting relay for each signal governed by traffic approaching the signal, a normally deenergized light-out relay for each signal, a normally energized checking relay for each signal, a lighting circuit for each signal including a back contact of the associated approach lighting relay and the winding of the associated light-out relay; a circuit for each checking relay including a back contact of the associated light-out relay, a front contact of the associated approach lighting relay, and the lamp filament of the associated signal; and a line circuit for each polarized line relay controlled by the checking relay for the signal next in advance.

11. In combination with a section of railway track, a light signal for governing traffic entering said section, said signal having a lamp, a polarized line relay for said signal for governing the indication provided by the signal, a polarized line circuit for said relay controlled by traffic conditions in advance of said signal, means for at times supplying lighting current to said signal, a checking relay, a checking circuit including the lamp filament of said signal for at other times supplying a checking current to the signal and for energizing said checking relay, a slow acting relay controlled over a contact of said checking relay, and a line circuit controlled by said slow acting relay for governing traffic approaching said signal.

12. In combination with a section of railway track, an approach energized light signal for said section comprising a main and an auxiliary light unit, a polarized line relay for each signal for governing the indication provided by the signal, a polarized line circuit for said relay controlled by traffic conditions in advance of said signal, means for at times supplying lighting current to said signal, means for at other times supplying a checking current to the main unit of said signal of insufficient value to light the lamp of said main unit, and means effective upon the interruption of said checking current in the event of failure of said lamp for lighting the lamp of said auxiliary light unit.

13. In combination with a section of railway

track, a signal for governing traffic entering said section including a mechanism and a lamp, means governed by traffic conditions in advance for operating said mechanism to a given position to cooperate with said lamp to display a first indication, and means controlled by said mechanism for displaying a second indication if said mechanism is operated for displaying said first indication but said lamp is burned out.

14. In a railway signaling system, in combination, spaced signals each having an incandescent lamp, a polarized line circuit for controlling the indication displayed by each signal, a filament check relay at each signal connected in series with a source of energy and the signal lamp filament, a control relay for each signal controlled by contacts of its signal and in turn connected to pole change the line circuit to the signal to the rear, and a front point of the check relay in the energizing circuit of the control relay.

15. In a railway signaling system, in combination, spaced signals each having an incandescent lamp, a polarized line circuit for controlling the indication displayed by each signal, a filament check relay at each signal connected in series with a source of energy and the signal lamp filament, a control relay for each signal controlled by contacts of its signal and in turn connected to pole change the line circuit to the signal to the rear, and a front contact of the check relay in the line circuit to the signal to the rear.

16. In a block signaling system, signals of the movable color screen type having contacts operated by said screen in accordance with the indication displayed by the signal, a track circuit next in advance of each signal and having a track relay, a polarized line circuit associated with each signal for controlling the signal next in the rear, and means associated with each signal and at all times including and dependent upon the contacts of two slow release relays controlled by the contacts of that signal and the track relay for that signal for at all times controlling the continuity and polarity of energization of said line circuit for the signal next in the rear.

HENRY S. YOUNG.
